(57) CLAIM

The ornamental design for the table base, as shown and described.

DESCRIPTION

FIG. 1 is a perspective view of a table base in accordance with the present invention;

FIG. 2 is a front view of the table base, the back view being a mirror image thereof;

FIG. 3 is a top view of the table base, the bottom view is not illustrated as it forms no part of the present invention;

FIG. 4 is a right side view of the table base, the left side view being a mirror image thereof;

FIG. 5 is a perspective view of an alternate embodiment of the table base in accordance with the present invention;

FIG. 6 is a front view of the alternate embodiment of the table base, the back view being a mirror image thereof;

FIG. 7 is a top view of the alternate embodiment of the table base, the bottom view is not illustrated as it forms no part of the present invention; and,

FIG. 8 is a right side view of the alternate embodiment of the table base, the left side view being a mirror image thereof.

The broken lines are for environmental purposes only and form no part of the claimed design.
